AUTOMATIC COPYING LATHE FOR SHOE LASTS

Laurence E. Tepham, Wenham, and Clyde L. Knott, Beverly, Mass., assignors to United Shoe Machinery Corporation, Flemington, N. J., a corporation of New Jersey

Application March 16, 1946, Serial No. 654,924

13 Claims. (Cl. 142—15)

1

This invention relates to copying lathes, and its purpose is to provide automatic means for varying the angular turning speed of a lathe in accordance with radial dimensions and surface characteristics of the form to be copied. These dimensions and characteristics, when utilized as herein set forth, will permit relatively rapid turning speed under the more favorable turning conditions, and will retard the speed only when less favorable conditions require retardation, and thereby insure a corresponding increase in the productive capacity of a lathe consistent with accuracy of the products.

As herein illustrated, the speed-regulating equipment provides three automatic controls derived from a pair of mated models and two individually movable swing frames in which the models are mounted. One of the swing frames is hereinafter termed the "master swing frame" because its motions determine the shape of the product. Whichever model is mounted in the master swing frame becomes the "master model," while the mate thereof serves as a "pilot model" in the other swing frame which is termed "pilot swing frame." The two models are interconnected to rotate at equal speeds despite the fact that their speeds are not constant. Moreover, the face plates or chucks for driving them are out of angular phase, their phase differential being an arbitrary quantity, preferably about 10°, and the pilot model being ahead of the master model in that respect.

A variable-speed driving unit is provided to rotate the models and the work block, and its driving speed is governed by a regulator the movements of which are responsive to the three automatic controls hereinbefore mentioned. One of these controls, termed "radius control," derives its speed-regulating movements solely from the pilot swing frame, and its effect is to vary the speed of the driving unit inversely according to the distance between the pilot model-wheel and the turning axis of the pilot model. The lengths of the several radii of the pilot model are the essential factors that enable this control to regulate the angular turning speed of the models and the work-block.

One of the other automatic controls above mentioned can be utilized to vary the turning speed of the models according to the steepness of acclivities and declivities in their contours, and when so utilized it will prevent excessive velocity of the swing frames that would otherwise occur if full advantage is to be taken of the more favorable operating conditions to increase the turning speed. This automatic control is here-

2

inafter termed "sustaining modifier" because its speed-regulating effect is sustained in accordance with the angular extent of the acclivities and declivities of the models.

5 The third automatic control is hereinafter termed "transitory modifier" because it can be utilized to modify the turning speed with a transitory effect. Its purpose is to prevent sudden acceleration of the master swing frame in response to the more abrupt deviations in the contour of the master model. The desired effect is obtained by utilizing the more abrupt deviations in the pilot model, which come into play earlier than those of the master model, to produce transitory components of speed reduction before the corresponding deviations in the master model come to the master model-wheel, and to eliminate such transitory components gradually as soon as they reach their peak. In 10 this respect, the pilot swing frame detects, in advance, the needs of the master swing frame and activates the transitory modifier accordingly.

15 The components of speed-regulation derived 25 from the several controls, whether increments or decrements, are communicated to three separate input points of an integrator in triangular relation to each other. Another point of the integrator, constituting the output point thereof, is connected to the speed regulator which is thereby rendered responsive to any one, any two, or all three of the automatic controls.

20 The novel features of the present invention are 30 illustrated as applied to a copying lathe of the type set forth in United States Letters Patent No. 2,072,228, granted March 2, 1937, on an application filed in our names, but this difference is to be observed, namely, the patented lathe includes only one swing frame, while the present invention utilizes a supplemental swing frame for the pilot model in addition to a master swing frame for the master model and the work-block. The former lathe and that herein illustrated have identically the same provisions for girth-35 grading and length-grading, with this exception: the model-wheel carriage of the instant lathe is provided with two model wheels, one for the master model and the other for the pilot model, and they are interconnected by means arranged 40 to impart girth-grading movements to the pilot model wheel commensurate with those of the master model wheel.

45 Since high velocity of a heavy rotor in a driving unit is incompatible with acceleration and deceleration, an electric motor alone is ill-suited 50 to effect variations in turning speed as promptly

as required to satisfy the purpose of the present invention. Because of this consideration the instant lathe is driven by a hydrodynamic variable-speed unit of a well known commercial type that operates with relatively slow angular velocity and with positive effect not only to accelerate but also to decelerate its rotational output. It includes a rotary pump the rotor of which may be driven at a constant speed by an electric motor, and the stator of which may be shifted to and fro to regulate its hydraulic output. The hydrodynamic unit illustrated herein is of the type set forth in United States Letters Patent No. 2,074,068, granted March 16, 1937, and the means for regulating the speed of its rotational output is of the type set forth in United States Letters Patent No. 2,105,454, granted January 11, 1938. The applicant of both of these patents is Walter Ferris.

Of the drawings,

Fig. 1 is an elevation of the left-hand end of a lathe embodying the invention, portions of the swing frames being broken away and both models being represented in section;

Fig. 2 is a top plan view of the lathe. For a top plan view of the models, a work-block, etc. see Fig. 15;

Fig. 3 is a phantom elevation corresponding to Fig. 1 but illustrating the transmission means for rotating the models and the work-block;

Fig. 3a is a sectional elevation of transmission gearing for driving the screw-shaft that feeds the cutter-carriage and the model-wheel carriage;

Fig. 4 is a top plan including elements of the transmission means, the model-wheel carriage, and some of the elements for regulating the turning speed;

Fig. 5 is a sectional elevation of an assemblage of elements of the model-wheel carriage and the master swing frame;

Fig. 6 is an end elevation of an assemblage of elements of the girth-grinding mechanism left out of Fig. 5 foreground;

Fig. 7 is an end elevation, partly in section (line VII—VII of Fig. 8), of the assemblage represented in Fig. 6;

Fig. 8 is a plan section indicated by line VIII—VIII in Fig. 6;

Fig. 9 is a vertical section (line IX—IX in Fig. 11) of a modifier for regulating the speed of the lathe according to the steepness of the surfaces of both models;

Fig. 10 is a plan section (line X—X in Fig. 9) of a linkage by which both modifiers (Figs. 9 and 12) are operated with motions derived from the differential member (Fig. 14);

Fig. 11 is an end elevation, partly in section, of an assemblage including the three-point integrator, the speed regulator operated thereby, and the two modifiers illustrated respectively in Figs. 9 and 12;

Fig. 11a is a top plan view of the integrator which has three input points of motion and one output point for operating the speed regulator;

Fig. 12 is a front elevation, partly in section, of the assemblage represented in Fig. 11 and some additional elements included in Figs. 1 and 4 (see line XII—XII in Fig. 11);

Fig. 13 is a schematic view in end elevation, as in Fig. 1, of an assemblage including the swing frames, the models, and a linkage of the radius control;

Fig. 14 is an end elevation of an assemblage including the speed regulator, the three-point

integrator and a differential member by which both modifiers are operated according to swing frame differentials;

Fig. 15 is a top plan view including both models and a work-block, face plates for supporting their butt ends and driving them, and tail stocks for supporting their toe ends; and

Fig. 16 represents a cross-sectional contour of the pilot model.

10 Since many of the details of construction and features of organization herein illustrated are the same as, or similar to, corresponding details and features shown and described in our earlier development (United States Patent No. 2,072,228)

15 above mentioned, the present description will be abbreviated with respect to them. It is to be understood, nevertheless, that the present invention is applicable to lathes capable of turning a complete last in one piece instead of the type selected, which is designed to turn foreparts and heel parts individually.

Fig. 2 includes a cutter-carriage 10 and a model-wheel carriage 11 both slideable on guide rails 12 and 13 provided by the main frame 14, an electric motor 15 mounted on the carriage 10, a rotary cutter head 16 carried by the shaft of the motor, a screw-shaft 17 having a left-hand thread for feeding the carriage 10 and a right-hand thread for feeding the carriage 11, and a long swing frame 18 in which two face plates 19 and 20 and two tail stock centers 21 and 22 are arranged on a common turning axis. The face plates are both affixed to a driven spindle 23 and each is provided with crossed ribs or keys (Fig. 15), those of the plate 19 to be nested in intersecting grooves 24 in the butt end of a work-block 25, and those of the plate 20 to be nested in similar grooves 26 in the butt end of a model 27. These elements are separated in this view merely to show clearly their interlocking formations. A small socket 28 is formed in the toe end of the block 25 to receive the center 21, and a corresponding socket 29 is in the toe end of the model to receive the center 22.

45 One of the novel features of the lathe is an auxiliary swing frame 30 located at the rear of the main frame 14 opposite the model-carrying section of the swing frame 18. For descriptive and identifying purposes the swing frame 18 is hereinafter termed "master swing frame" and the swing frame 30 is termed "pilot swing frame."

50 The latter is shorter and much less heavy than the master swing frame, and its load is less heavy than that carried by the master swing frame. The only load to be carried by the pilot swing frame is a pilot model 31, which is the mate of the master model 27. Since the inertia factor of the pilot swing frame (including load) is very much less than that of the master swing frame, it has appreciably less tendency to cause overtravel during periods of outswing, and requires less power to reverse its direction of travel. The pilot swing frame carries a tail-stock center 32 and a face plate 34 for supporting and rotating the pilot model. This face plate is a duplicate of the face plate 20 and is affixed to a driven spindle 33.

55 The master swing frame 18 includes a horizontal rock-shaft 35 (Figs. 4 and 8) and an extension member 140 affixed thereto and supported by a trunnion 83 fastened in the main frame 14. When a model is set up in this swing frame it is held against a model-wheel 36 by the force of a spring 37 connected to an arm of the swing frame (see upper end of Fig. 2). The pilot swing

frame 30 likewise includes a rock-shaft 38 journaled in bearings in the main frame 14. A model set up therein is held against a model-wheel 39 by the force of a spring 40 (Figs. 1 and 2) connected to an arm of this swing frame.

Although both model-wheels are mounted on the carriage 11 they are movable toward and from each other for girth-grading, and for this purpose the carriage is provided with parallel bearings for two slideable rack-bars 41, 42 (Figs. 4 and 5) both intermeshed with an interposed pinion 43. The latter turns on a pivot affixed to the carriage and insures equal but opposed end-wise movements of the rack-bars. Each rack-bar carries a boss 44 rigidly related thereto. A pivot pin 45 connects an arm 46 and one boss 44, while a similar pin connects an arm 47 and the other boss. The model-wheels 36 and 39 are carried, respectively, by the arms 46 and 47. The girth-grading movements are communicated to the arm 46 by a lever 48 (Fig. 5) as in the lathe illustrated in the aforesaid Patent No. 2,072,228. This lever is slidably mounted on a rockshaft 49 and a parallel bar 50 affixed thereto. The rockshaft is journaled in bearings in the frame 14. The loaded end of the arm 47 is supported and guided by a radius link 48' just as that of the arm 46 is supported and guided by the lever 48. The link 48' is carried by the carriage 11 and connected thereto by a pivot-pin 49'.

In Fig. 2 the cutter-carriage 10 and the model-wheel carriage 11 stand in their initial locations, widely separated, to be driven toward each other by the screw-shaft 17 as a turning operation progresses. A nut 51 (Fig. 4) anchored to the underside of the carriage 10 cooperates with the left-hand thread of the screw-shaft, while a corresponding nut 52 (Fig. 5) having swivel connection with the carriage 11 cooperates with the right-hand thread of that shaft. The swivel connection provides for relatively slow automatic turning of the nut 52 for whatever length-grading may be called for. An adjustable track 53 (Fig. 2) pivotally connected to the frame 14 determines the extent to which the nut 52 will be turned, if at all, and since this length-grading mechanism is like that illustrated in the aforesaid Patent No. 2,072,228, no further description thereof is needed here.

A gear 54 (Figs. 3a and 4) is affixed to the screw-shaft 17 between its screw portions, and rotation thereof is derived from a shaft 55 located at the left-hand end of the lathe. The shaft 55 extends from front to rear and is journaled in bearings in the main frame 14. The connections for driving the screw-shaft include a worm 56 and gear 57, a shaft 58, spiral gears 59 and 60, a shaft 61, and a worm 62, the latter being in mesh with the gear 54. The shaft 61 is journaled in a cradle 63, as heretofore, and the latter is hung on the shaft 58 about which it may be rocked to disengage the worm 62 from the gear 54 at the conclusion of a turning operation.

The shaft 55 (Figs. 3 and 4) also carries bevel gears 64 and 65, the former for driving a gear train 66 carried by the master swing frame 18, and the latter for driving a corresponding gear train 67 carried by the pilot swing frame 30. The gear train 66 includes a bevel gear 68 and a spur gear 69 rigidly related to each other and both mounted on a cylindrical portion of the rock-shaft 35 about which they may rotate without turning the latter. Likewise, the gear train 67

includes a bevel gear 70 and a spur gear 71, rigidly related and rotatably mounted on a cylindrical portion of the rockshaft 38. The gear train 66 is located at the left-hand end of the swing frame 18, but two corresponding gear trains (not shown) are also carried by this swing frame, one at its right-hand end and the other about midway between its ends where one of the gears, 72 (Fig. 15), is affixed to the spindle that carries the face plates 19 and 20. The three gear trains carried by the swing frame 18 are all connected by a common transmission shaft 73 (Fig. 3), as heretofore.

In like manner, the pilot swing frame 30 carries a gear train represented by the gear 74 (Fig. 15) for driving the face plate 34. The trains 67 and 74 are connected by a transmission shaft 75 (Figs. 2 and 3). When the shaft 55 is in rotation the three face plates 19, 20 and 34 will all be driven at equal speeds, but the direction of rotation of the pilot model 31 will be the reverse of that of the master model 27 and the work-block 25. Furthermore, considering the angular relation of each model to its points of contact with its model-wheel, the models are out of angular phase with each other, the pilot model being slightly ahead of the master model in this respect. The extent of priority of the pilot model is optional, within an undetermined limit, but a phase differential of ten degrees is satisfactory for turning lasts. The phase differential is one of the fundamentals on which the present invention is predicated. By way of explaining the effect of such a differential, it is pointed out that all motions of the master swing frame 18 are anticipated by corresponding motions of the pilot swing frame 30, and that the earlier motions of the latter are utilized to increase or decrease, as the case may be, the turning speed of all the face plates simultaneously and equally. The motions of the master swing frame are also utilized for the same purpose, but they are integrated with those of the pilot swing frame to provide composite effects in the matter of speed regulation.

The source of rotation for driving the shaft 55 is a variable-speed motor 76 (Fig. 3) which, for technical reasons, may be a hydrodynamic unit of the type set forth in the aforesaid Ferris Patents Nos. 2,074,068 and 2,105,454. This unit derives its power from an electric motor 77 of the constant speed type, and its regulation of driving speed from an adjustable oscillatory regulator 78. A spring 79 connected to the arm of the regulator normally pulls the arm down to increase the driving speed, but its force is opposed by a vertically movable rod 80 also connected to the arm. A driving pulley 81 on the shaft of the unit 76, and a pulley 82 on a countershaft 83 are connected by belts 84. A train of gears 85 transmits rotation from the shaft 83 to the driving member 86 of a toothed clutch the driven member 87 of which is affixed to the shaft 55. The driving member 86 may be shifted axially on the shaft 55 to engage and disengage the member 87 as heretofore, but the present invention is not concerned with starting and stopping the operation of the lathe. It is concerned with automatic regulation of the turning speed of the models and a work-block through the medium of controls yet to be described.

Control integrator

The vertical rod 80 (Figs. 1, 11, 12 and 14) connects the speed regulator 78 and a kinetic integrator 90 which, according to the scheme here-

inafter described, receives components of speed-regulating movement from three individually movable pendular links 91, 92 and 93 on which it is suspended with ball-and-socket connections that enable it to rock in all directions. These connections are located in triangular relation (Fig. 11a), and the triangular area defined by them is provided with many holes 94 in any one of which a socket member 95 may be attached. The member 95 and the upper end of the rod 89 form another ball-and-socket connection for shifting the speed-regulator to and fro.

When the lathe is in operation, outward movements of the pilot swing frame raise the pendular link 91, and inward movements lower it, with corresponding components of rocking movement of the integrator 90. Although these components may be compounded with other components derived from the links 92 and 93, the purpose of the link 91 is to retard the driving speed of the unit 76 as the effective radius of the pilot model 31 (reckoned from its turning axis) grows longer, and increase the driving speed as that effective radius grows shorter. It follows that the turning speed of both models and the work-block will be retarded or increased simultaneously, as the case may be, since their angular coordination is maintained by the interconnection of their transmission gearing. Furthermore, the relative or proportional kinetic value of these components may be varied by adjusting the socket member 95 toward or from the point where the rod 91 and the integrator are connected.

The linkage about to be described is provided to raise and lower the link 91: an arm 96 (Figs. 1, 2, 4, 12 and 13) is fastened to the rockshaft 38 of the pilot swing frame, and a bell-crank 97 is loosely mounted on a trunnion 88 that supports one end of the master swing frame. This trunnion is fixed in the main frame 14. A link 98 connects the arm 96 and the bell-crank to oscillate the latter in timed relation to the movements of the pilot swing frame. A ball-end stud 99 carried by the bell-crank (Figs. 8 and 12) has operative connection with a socket at the upper end of the link 91. It is to be understood that the linkage just described receives no motion from any source other than the spring 40 (Fig. 1) and the pilot swing frame, and that the speed-regulating components communicated thereby to the integrator 90 anticipate all movements of the master swing frame by an interval corresponding to the phase differential between the two swing frames.

The ball-end stud 99 has a cylindrical portion on which a differential lever 100 is mounted. One end of this lever has sliding connection with a stud 101 carried by an arm 102 of the master swing frame. Consequently, the differential lever is carried by two fulcrum studs one of which (99) moves up and down in synchronism with the earlier movements of the pilot swing frame, and the other of which (101) moves up and down in synchronism with the later movements of the master swing frame. The lever 100 is therefore operated conjointly by both swing frames according to their phase differential. The operating or output end of this lever and a rod 103 suspended therefrom are connected by a pivot pin 104 the center of which travels up and down in arcs tangent to the axis of the master swing frame. Furthermore, the elements are so organized that the center of the pin 104 will registers with the axis last mentioned whenever 75

the turning axes of the two models are equidistant from the respective model wheels, however great the distance may be. In operation, the output end of the differential lever will move up and down according to the difference in radial length between the contact points on the models and the respective turning axes. At some stages these up-and-down movements may be rapid, and at other stages they may be slow. At some stages the pin 104 may vibrate above its median level without moving below the latter, at other stages it may vibrate below that level without rising above it, and at still others it may vibrate between points above and below that level, but, wherever it may be, it will not remain at one point for any appreciable period of time.

The foregoing discussion of the behavior of the differential lever is intended to prepare the way for descriptions of two hydraulic modifiers both activated by that lever to furnish components of speed-regulating movement to the integrator 90 and thereby modify the kinetic output of the latter according to the contour characteristics of both models. One of these modifiers raises and lowers the pendular link 92 (Fig. 11) with a sustaining effect to prevent excessive velocity of the swing frames by reducing the turning speed of the models when steep acclivities and declivities of contour are in contact with the model wheels. The other modifier enables sudden surges, slackenings and reversals of the pilot swing frame to raise the pendular link 93 with a transitory effect of comparatively short duration and thereby furnish special components of speed reduction whenever, surges, slackenings and reversals of the heavier and less sensitive master swing frame are about to occur.

Hydraulic modifiers

40 The rod 103 (Figs. 8, 9, 11, 12 and 14) transmits up and down motions from the differential lever 100 to an arm 105 affixed to a rockshaft 106 journaled in bearings in a casing 107. Another rockshaft 108 is likewise journaled and is parallel with the shaft 106 and spaced therefrom. Both hydraulic modifiers are located between these rockshafts. Two forked arms 109 affixed to one of the rockshafts carry a pivot pin 110, and two similar arms 109 affixed to the other rockshaft carry another pivot pin 110. These pins are connected by a tie-rod 111 that maintains a constant distance between them and transmits motion from one to the other. Each pin 110 carries two similar pressing pads 112 and 125, the two pads 112 facing each other to operate the sustaining modifier, and the two pads 125 facing each other to operate the transitory modifier.

Sustaining modifier

The sustaining modifier comprises two opposed hydraulic pulsators 113 and 114 (Fig. 9) each a normally expanding bellows, a large duct 115 in a fixture connecting their inner ends, a cylinder 116 adjoining the duct, and a ram 117 movable up and down in the cylinder. The chamber formed by these elements is filled with liquid, but the latter is not indicated in the drawings. The upper end of the ram engages and supports an arm 118 affixed to a rockshaft 119 provided with an arm 120 (Fig. 11) from which the link 92 is suspended. One input point of the integrator 90 is thus supported by a column of liquid in the cylinder 116. Each bellows is contained in a fixed cage 121, and the outer end of each cage is open

and provided with a lip 122 which serves as a stop to arrest the back strokes of the end wall 123 of the corresponding bellows. The pads 112 are adapted to enter the cages 111 to compress the respective bellows one at a time, but never both at once because the distance between the confronting faces of the pads is just equal to the greatest distance between the outer faces of the walls 123. Fig. 9 represents a typical relation in which the bellows 113 is partially compressed by the pad abutting its left end, while the opposite pad is retracted from the right end of the bellows 114 which abuts its arresting lip 122. The ram 117 is raised above its normal position in consequence of compressing the bellows 113, but the same effect would be produced by compressing the bellows 114 to an equal extent.

It may now be understood that the ram 117 will stand at its lowest position only when both bellows are distended as far as their arresting lips 122 will permit, and that this position corresponds to the neutral or median position of the assemblage comprising the pads 112 and the tie-rod 111. It is also to be understood that the neutral position of the pad assemblage corresponds to any position of the differential lever 100 (Fig. 13) that locates the center of the pin 104 in coincidence with the axis of the master swing frame. Any upward movement of the pin 104 above that axis will compress the bellows 113, and any downward movement below that axis will compress the bellows 114. In another sense, the last statement means that the sustaining modifier will maintain a variable component of speed reduction whenever the swing frames are unequally displaced by acclivities and declivities of the models, but not when the turning axes of the two models are equidistant from the respective model-wheels, and that the magnitude of this component will vary as the inequality of such displacement varies. Extending this analysis further, the steeper acclivities and declivities in the surfaces of the models will produce greater components of speed reduction than the less steep ones will produce, since the modifier is operable conjointly by both swing frames according to their phase differential.

Transitory modifier

This modifier comprises two opposed hydraulic pulsators 126 and 127 of equal capacity (Fig. 12) each a normally expanding bellows, a restricted duct 128 in a fixture connecting their inner ends, two cylinders 129 and 130 communicating with the duct, two vertically movable rams 131 and 132, one in each cylinder, and a needle-valve 133 arranged to regulate the flow of liquid to and fro between the cylinders. The chamber formed by these elements is filled with liquid, but the latter is not indicated in the drawing. Unlike the sustaining modifier, no stops are provided to arrest the back strokes of the outer ends of the bellows 126 and 127, and the latter therefore remain against the respective pads 125 under all conditions of operation. Both rams 131 and 132 are arranged to support an arm 134 when the liquid is in equilibrium. This arm is fastened to a rockshaft 135 provided with an arm 136 from which the link 93 is suspended to support one input point of the integrator 90.

In operation, any upward motion of the rod 103 derived from the differential lever 100 will compress the bellows 126 and permit a commensurate expansion of the bellows 127. If the

quantity of liquid thus displaced exceeds the relief afforded by the needle-valve 133 the surge produced by the bellows 126 will drive the ram 131 upward, with a corresponding component of speed-reducing movement of the integrator 90, but the effect thus produced will be transitory because the flow of liquid past the needle-valve will tend always to restore equilibrium of the liquid in both bellows and both cylinders 129, 130. 5 In like manner, any downward motion of the rod 103 will compress the bellows 127 and relieve the bellows 126, and the effect on the integrator will be the same as that described above, but in this case the ram 132, instead of the ram 131, will be 10 the one to furnish a transitory component of speed-reducing movement to the integrator. The speed-reducing components produced by the transitory modifier occur whenever a surge of the pilot swing frame in either direction is so 15 great or sudden as to overload the relief afforded by the needle-valve 133, and these components, if the needle-valve be correctly adjusted, begin to lose their effect immediately upon reaching their peak. Nevertheless, their effect may be prolonged 20 sufficiently by the needle-valve to prevent too rapid turning of the master model at those stages 25 when inertia of the master swing frame might otherwise cause separation of the master model and its model-wheel.

The magnitude of these components may be 30 regulated independently of their periods of duration by shifting the output socket member 95 (Fig. 11a) toward or away from the input link 93, and, in like manner, the magnitude of the 35 speed-reducing components derived from the sustaining modifier may be regulated by shifting the same socket member toward or away from the input link 92.

Now, supposing that Fig. 16 represents the 40 cross-sectional contour of a forepart model in a plane intersecting the cone portion thereof, and that this model is set up in the pilot swing frame while its mate is set up in the master swing frame, the pilot model will rotate counterclockwise about its turning axis, represented by a dot x , and thereby bring the points a , b , c , d and e of this contour successively into contact with the pilot model-wheel. The corresponding points on the master model will be brought into contact 45 with its model-wheel later than those of the pilot model by an interval constituting the phase differential which may be considered as 10° .

Following the point of contact as it would 50 progress in a clockwise direction with respect to the pilot model, and considering point a as a starting point for no reason except that the radial dimension of the model is shortest at this point, the pilot swing frame will swing out from a to b , thereby furnishing speed-reducing components to 55 the integrator 90 (Fig. 11a) by raising the input link 91. During the same period the acclivity of the model contours will cause collapsing of the bellows 113 (Fig. 9). Consequently, the sustaining modifier will furnish additional speed-reducing 60 components to the integrator 90 by raising the input link 92. Although the steepness of the acclivity increases from a to b , the increase is gradual and may not produce much, if any, speed-reducing action on the part of the transitory modifier (Fig. 11). However, if any such 65 action does occur, it will not begin until point b of the pilot model has nearly reached the point of contact.

As point b of the pilot model is leaving, and 70 point b of the master model is approaching, the

point of contact, the differential lever 100 (Figs. 1 and 13) will be rocked suddenly in the clockwise direction, partly by downward movement of the fulcrum stud 99 and partly by upward movement of the fulcrum stud 101. At this stage the integrator 98 will receive speed-reducing components from the bellows 114 of the sustaining modifier, and additional speed-reducing components from the bellows 127 of the transitory modifier. The latter components will cease when point *b* of the master model passes the point of contact.

Since the effective radial length of the models grows shorter from *b* to *c*, the input link 91 of the integrator will furnish speed-increasing components, but these will be partially, if not wholly, counteracted by speed-reducing components due to the declivity and the corresponding action of the sustaining modifier (bellows 114) and the input link 92.

The declivity from *c* to *d* (Fig. 16) is not steep near point *c* but is very steep near point *d*, and the speed-reducing effect of the sustaining modifier (bellows 113) will be developed accordingly. At the same time, the speed-reducing effect of the radius control (input link 91) will not only be increased but will be added to that of the sustaining modifier. If these two controls do not retard the turning speed enough to maintain equilibrium of the liquid in the transitory modifier the bellows 126 will raise the ram 131 and the input link 93, thereby retarding the speed still more.

As the point of contact on the pilot model advances from *d* to *e*, the outswing of the pilot swing frame will cease abruptly and the back-swing thereof will begin abruptly, but since the inertia factor of the master swing frame is much greater than that of the pilot swing frame, the master swing frame requires greatly reduced turning speed until it, too, has passed the critical stage corresponding to the run from *d* to *e* on the master model. The radius control will undergo only an insignificant change during this stage, but the transitory modifier (bellows 127) will receive a great surge from the differential lever 100 as the fulcrum stud 99 drops while the stud 101 continues to rise. Consequently, the input link 93 will rise with great speed-reducing effect. The same rocking motion of the differential lever 100 will transfer the speed-reducing effect of the sustaining modifier from the bellows 113 to the bellows 114, but the period of transition will be so short that little, if any change of speed will be derived from that modifier.

As the effect of the transitory modifier subsides at or near point *e*, the effect of the sustaining modifier will increase with the steepness of the declivity, but beyond that point the diminishing radius of the pilot model will lower the input link 91 of the integrator while, at the same time, the diminishing steepness of the declivities of both models will lower the input link 92. Consequently, the turning speed will receive accelerative components from two controls (radius control and sustaining modifier) from point *e* to point *a*.

A recapitulation of the three automatic speed-regulating controls could be reduced to the following terms; viz., the radius control is not affected by the phase differential, but utilizes only the outswing of the pilot swing frame to furnish speed-reducing components, and back-swing of that same swing frame to furnish speed-increas-

ing components. The sustaining modifier requires phase differential of two models and two swing frames and is operated conjointly by both swing frames according to their differential. The effect of this modifier varies according to the steepness of acclivities and declivities. The transitory modifier requires the phase differential of two swing frames to enable sudden or abrupt surges and reversals of the pilot swing frame to moderate the corresponding surges and reversals of the master swing frame. The motions of the radius control may be rendered ineffective by placing the socket member 95 (Fig. 11a) on a line intersecting the input links 92 and 93; those of the sustaining modifier may be rendered ineffective by placing that socket member on a line intersecting the input links 91 and 93; and those of the transitory modifier may be rendered ineffective by placing the socket member on a line intersecting the input links 91 and 92.

Although the linkage for imparting girth-grading movements to the model-wheel 33 is the same as the corresponding linkage shown in the aforesaid Patent No. 2,072,228, a brief description thereof now follows. A rocker 143 (Figs. 4, 6, 7 and 8) affixed to the rockshaft 35, and constituting a part of the master swing frame, carries two trunnions 141, 142, lying on a common axis, but the confronting ends of the trunnions are spaced to clear elements located between them. A pair of links 143 mounted one on each trunnion are connected by a pivot pin 144 which extends through a link 145. The latter connects the pin 144 and an arm 146 affixed to the rockshaft 49 (Fig. 5) from which the model-wheels derive their grading motion. The distance between the axis of the pin 144 and that of the trunnions is exactly equal to that between the axis of the rockshaft 35 and the axis of the trunnions. The pin 144 may therefore be placed above, below or in alignment with the axis of the rockshaft 35. In the latter relation the pin 144 and the rockshaft 49 will remain stationary while the master swing frame is in motion, and the girth-grading ratio will be 1 to 1. Grading up requires placing the pin 144 below, and grading down requires placing the pin above the axis of the rockshaft 35. For this purpose the lathe is provided with manually operable adjusting means including a crank 147 (Figs. 1, 2 and 12), a rotatable shaft 148, gearing (not shown herein), and a link 149 (Fig. 6) connecting the gearing and the pin 144. This link may be adjusted by the crank 147 to shift the pin 144 up and down to any selected grading position.

The link 150 (Figs. 7 and 8) and the arm 151 are provided to facilitate assembling the rockshaft 35 and the rocker 140 in the main frame 14, and to tie them in a constant angular relation. The arm 151 is pinned to the rockshaft, while the link 150 is mounted on the trunnion 141. When the link and the arm 151 are connected by a screw 152 the rocker 140 becomes, in effect, a part of the master swing frame.

Having described our invention, what we claim as new and desire to secure by Letters Patent of the United States is:

1. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both

of said rotatable means at equal speeds, said rotatable means being less than 90° out of angular phase with each other as between the two models, an adjustable regulator connected to said driving unit for varying the driving speed thereof, and movable linkage connecting the regulator and the pilot swing frame whereby swing of the latter is transmitted to the regulator for shifting the same to and fro.

2. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being less than 90° out of angular phase with each other as between the two models, an adjustable regulator connected to said driving unit for varying the driving speed thereof, a differential member, means connecting one point of the differential member to the master swing frame and means connecting another point of the differential member to the pilot swing frame, and a member engageable with the regulator and connected to a third point of said differential member for shifting said regulator.

3. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being less than 90° out of angular phase with each other as between the two models, an adjustable regulator connected to the driving unit for varying the driving speed thereof, means for transmitting motion of the pilot swing frame to said regulator, and a movable member interposed in the motion transmitting means for modifying the effects of said motion transmitting means on the regulator, said modifying member being displaceable conjointly by both of the swing frames according to their phase differential.

4. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being less than 90° out of angular phase with each other as between the two models, an adjustable regulator connected to the driving unit for varying the driving speed thereof, differential means operably connected to both swing frames for movement thereby, and means connecting said differential means to said regulator.

5. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit,

transmission means operable by said unit for driving both of said rotatable means at equal speeds, said rotatable means being out of angular phase with each other as between the two models, an adjustable regulator connected to the driving unit for varying the driving speed thereof, a kinetic integrator for shifting the regulator to and fro, means connecting the pilot swing frame and one point of said integrator for moving that point to and from in synchronism with the movements of that swing frame, and modifying means connected to another point of the integrator for moving that point with speed-regulating components, said modifying means being connected to both of the swing frames to be actuated by them conjointly according to their phase differential.

6. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being out of angular phase with each other as between the two models, an adjustable regulator connected to said driving unit for varying the driving speed thereof, an angularly movable integrator having three points of suspension in triangular relation, means effectively connecting an output point of said integrator and the speed-regulator, displaceable members connected to and actuated by the pilot swing frame alone for furnishing speed-regulating components thereof to one of said three points of the integrator, a sustaining modifier, means connecting said sustaining modifier to another one of said three points for furnishing sustained speed-regulating components thereto, a transitory modifier, means connecting said transitory modifier to the third one of said three points for furnishing transitory speed-regulating components, and differential means for operating both of said modifiers at once, said differential means including members movably connecting the swing frames with both modifiers and actuated by both swing frames conjointly according to their phase differential.

7. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being out of angular phase with each other as between the two models, an adjustable regulator connected to said driving unit for varying the driving speed thereof, an angularly movable integrator, means including a member effectively connecting an output point of said integrator and the speed-regulator, movable members connecting the pilot swing frame and the integrator and actuated by the pilot swing frame alone for furnishing sustained speed-regulating components to one input point of said integrator according to radial variations of the pilot model, a sustaining modifier, means connecting said sustaining modifier to another input point of said integrator for furnishing sustained speed-regulating components, and a dif-

ferential lever having connections with said modifier, and means for operating said differential lever by both of said swing frames conjointly according to their phase differential.

8. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being out of angular phase with each other as between the two models, an adjustable regulator connected to said driving unit for varying the driving speed thereof, an angularly movable integrator, a member effectively connecting an output point of said integrator and the speed-regulator, members connecting the pilot swing frame and the integrator and actuated by the pilot swing frame alone for furnishing sustained speed-regulating components to one input point of said integrator according to radial variations of the pilot model, a hydraulic modifier means connecting said hydraulic modifier to another input point of said integrator for furnishing transitory speed-regulating components, and differential means for operating said modifier, said differential means being connected to and actuated by both of said swing frames conjointly according to their phase differential.

9. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being less than 90° out of angular phase with each other as between the two models, an adjustable regulator connected to said driving unit for varying the driving speed thereof, a differential member operatively connected to said swing frames for movements according to their phase differential, and mechanism activated by resultant pivotal movement of a portion of said differential member for shifting the regulator.

10. A copying lathe comprising a master swing frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being out of angular phase with each other as between the two models, an adjustable regulator connected to said driving unit for varying the driving speed thereof, a differential member, means connecting said differential member to both swing frames for movement according to their phase differential, a plurality of dissimilar modifiers, means connecting said modifiers to said differential member for movements thereby, a kinetic integrator for shifting the speed regulator, and connections operable by said modifiers respectively for actuating the integrator, said connections being connected to the integrator at separate points of the latter.

11. A copying lathe comprising a master swing

frame, rotatable means journaled therein for carrying a master model and a work-block, a master model-wheel, an individually movable pilot swing frame, rotatable means journaled in the latter for carrying a pilot model, a pilot model-wheel, a variable-speed driving unit, transmission means operable by said unit for driving both of said rotatable means at equal speeds, said rotatable means being less than 90° out of angular phase with each other as between the two models, an adjustable regulator connected to said driving unit for varying the driving speed thereof, a differential lever operatively connected to said swing frames for movements according to their phase differential, a modifier operatively interconnected with the regulator and said lever for imparting speed-retarding and -accelerating movements to said regulator in accordance with the steepness of acclivities and declivities in the contours of the models, and a second modifier operatively interconnected with the regulator and said lever for imparting transitory surges of supplemental speed-retarding and -accelerating movement to said regulator in accordance with deviations in the steepness of such acclivities and declivities.

12. A copying lathe comprising a master swing frame, rotatable means journaled therein for carrying a master model and a work-block, a master model-wheel, an individually movable pilot swing frame shorter and lighter than the master swing frame, rotatable means journaled in the pilot swing frame for carrying a pilot model, a pilot model-wheel, a variable-speed driving unit, transmission means operable by said unit for turning said rotatable means in both swing frames at equal speeds, the rotatable means in the pilot swing frame being less than 90° out of angular phase with and ahead of the rotatable means in the master swing frame, a regulator connected to the driving unit for varying the driving speed thereof, and mechanism including pivotally connected levers operated by swinging movements of the pilot swing frame alone for shifting the speed-regulator to and fro according to radial variations in the pilot model.

13. A copying lathe comprising a master swing frame, rotatable means journaled therein for carrying a master model and a work-block, a master model-wheel, an individually movable pilot swing frame, rotatable means journaled therein for carrying a pilot model, a pilot model-wheel, a variable-speed driving unit, transmission means driven by said unit for driving both of said rotatable means at equal speeds, the rotatable means of the pilot swing frame being less than 90° out of angular phase with and ahead of that of the master swing frame, a regulator for varying the driving speed of said unit, a pivotally suspended kinetic integrator actuated in part by movements of the pilot swing frame, means connecting said pilot swing frame to said regulator for shifting the regulator to and fro in accordance with radial variations of the pilot model, a differential lever, members supporting said lever and connected to both swing frames, a hydraulic ram arranged to impart speed-retarding impulses to the integrator, a pair of hydraulic pulsators both engaging the liquid for operating said ram, interconnected members actuated by said differential lever for operating said pulsators alternatively according to whether said lever is in one or the other of two adjoining divisions of its operative range, and stops arranged to arrest the back strokes of said pulsators
